LAMP

John J. Keal, Los Angeles, Calif., assignor to Modeline Company of California Inc., Los Angeles, Calif., a corporation of California

Application June 10, 1959, Serial No. 56,310

Term of patent 14 years

(Cl. D48—20)

Fig. 1 is a side elevational view of a lamp, showing my new design, the opposite side not shown being substantially the same.

Fig. 2 is an elevational view thereof as seen from the left of Fig. 1 with the shade omitted and standard fragmentarily shown for convenience of illustration.

Fig. 3 is an elevational view thereof as seen from the opposite side of Fig. 2.

Fig. 4 is a top plan view thereof as shown in Fig. 2.

The dominant features of my design reside in the portions shown in full lines.

I claim:

The ornamental design for a lamp, as shown and described.
